CLAIM

The ornamental design for an automobile wheel face, as shown and described.

DESCRIPTION

FIG. 1 is a front perspective view of the automobile wheel face;

FIG. 2 is a front view of the automobile wheel face;

FIG. 3 is a rear view of the automobile wheel face;

FIG. 4 is a left side view of the automobile wheel face;

FIG. 5 is a right side view of the automobile wheel face;

FIG. 6 is a top view of the automobile wheel face;

FIG. 7 is a bottom view of the automobile wheel face; and,

FIG. 8 is a side view of an automobile having front and rear automobile wheels, with a pair of the automobile wheel faces fitted in the front and rear automobile wheels, respectively.

The broken line showing illustrate environment and portions of an automobile wheel face that form no part of the claimed design.
